UNITED STATES PATENT OFFICE.

ELY BOCKSHE, OF MILWAUKEE, WISCONSIN, ASSIGNOR TO MODERN GRINDER MFG. CO., OF MILWAUKEE, WISCONSIN, A CORPORATION OF WISCONSIN.

GRINDER.

Application filed February 28, 1922. Serial No. 539,990.

To all whom it may concern:

Be it known that I, ELY BOCKSHE, a citizen of the United States, and resident of Milwaukee, in the county of Milwaukee and State of Wisconsin, have invented certain new and useful Improvements in Grinders; and I do hereby declare that the following is a full, clear, and exact description thereof.

The invention relates to grinders of the type on which Patent No. 1,006,026 was issued to J. M. Thompson, Oct. 17, 1911, for gear casing.

In the patent, the bearings for the grinding wheel shaft and the big gear shaft are all in one casting which is subjected to considerable strain and which cannot be readily replaced in case of breakage. The bearing for the grinding wheel is between the wheel and the gear for rotating same, and the bearing for the big gear shaft is entirely between the big gear and the crank arm. Thus for each of the shafts, only one bearing is provided. The provision of one bearing only is such that on wear, an angling of the shafts result. While this defect may be removed to a great extent by lengthening the bearings, the gear must then be made in a substantially conical shape, as shown in Figure 4 of the patent. Such a gear is difficult to construct and its shape necessitates the elongation of arms 25 and 26 with the consequently distant spacing of the point of support on the table from the crank arm. Thus when force is applied to the crank arm, there is an action of excessive leverage on the point of support.

Applicant's device comprises a grinding wheel shaft supported on a pair of bearings between which is positioned a pinion for rotating the shaft; a casing integral with the bearings, and having a side and peripheral wall, the side wall being integral with one of a pair of bearings supporting the shaft on which the crank arm is mounted. A second bearing is provided for this shaft integral with a cap for completely closing the casing, thus two bearings are provided for each shaft.

This structure effectively obviates tendency to angle, and the large gear is substantially flat, the supporting arms being

relatively close to the crank arm so that less leverage is developed.

With the above and other objects in view which will appear as the description proceeds, my invention resides in the novel construction, combination and arrangement of parts substantially as hereinafter described and more particularly defined by the appended claim, it being understood that such changes in the precise embodiment of the herein disclosed invention may be made as come within the scope of the claim.

In the accompanying drawing, I have illustrated one complete example of the physical embodiment of the present invention constructed according to the best mode I have so far devised for the practical application of the principles thereof, and in which:

Figure 1 shows a cross section substantially on the line 1—1 of Figure 2, illustrating the device, and

Figure 2 shows a side elevation with the grinding wheel removed.

Side wall 10 of the casing is integral with peripheral wall 11, bearing 12 centrally located and oppositely disposed bearings 13 and 14. Flange 15 is directed upwardly from peripheral wall 11 and by means of screws 16, cap 17 integral with bearing 18 is rigidly positioned thereon. Arms 19 and 20 are provided for purposes of support extending laterally from cap 17. Shaft 21 is mounted in bearings 12 and 18 and has crank 22 secured thereto, gear 23 being rigid with shaft 21. Gear 24 meshes with gear 23 and is rigid with shaft 25, which is provided with a head 26 preventing axial movement of annulus 27 abutting against bearing 13. Gears 23 and 24 are slidable longitudinally on shafts 21 and 25 respectively, to facilitate assembly.

I claim:

The combination of a shaft, a grinding wheel thereon, a gear rigid with said shaft, a pair of bearings for said shaft on either side of said gear, a peripheral wall of a casing and a side wall thereof, a substantially flat second gear, meshing with said first mentioned gear, a second shaft rigid with said second gear, laterally extending

from both sides thereof, a third bearing for one end of said shaft outwardly extending from said side wall, a crank on said second shaft, said pair of bearings, said peripheral wall, ~~said side wall and said third bearing~~ being integrally united, a cover, means securing said cover to said peripheral wall

and a fourth bearing integral therewith supporting the other end of said second shaft.

In testimony that I claim the foregoing ¹⁰ I have hereunto set my hand at Milwaukee, in the county of Milwaukee and State of Wisconsin.

ELY BOCKSHE.
